J. H. Waterford
ATTORNEY

UNITED STATES PATENT OFFICE.

WILLARD E. MARSH, OF MEMPHIS, TENNESSEE.

TENT SHELTER.

Application filed June 21, 1922. Serial No. 569,794.

To all whom it may concern:

Be it known that I, WILLARD E. MARSH, a citizen of the United States, residing at Memphis, county of Shelby, and the State of Tennessee, have invented certain new and useful Improvements in Tent Shelters, of which the following is a full, clear, and exact description, such as will enable anyone skilled in the art to make and use the same.

The objects of my invention are to provide a shelter tent adapted primarily to be used with a folding cot which tent may be readily and quickly erected over the cot and securely fastened in place. The further objects of my invention are to simplify and strengthen the shelter so that it may be stretched and drawn tight and securely closed in every respect by the occupant of the cot after he has retired thereon. It is the further object of my invention to provide a shelter which will be easy to dismantle and pack in a small roll.

With the above objects in view, my invention has relation to the arrangement and combination of the cot as will be more fully hereinafter set out in the drawings, specifications and claims.

In the drawings:—

Fig. 1, is a side elevation of my improved shelter tent in place over a cot, with one end of the shelter tent broken away to show the interior of the same.

Fig. 2, is an end elevation of the same.

Fig. 3, is a sectional elevation on an enlarged scale showing a detail of the upper end of the supporting posts and of one upper corner of the tent taken on the line III—III of Figs. 2 and 4 looking in the direction of the arrow.

Fig. 4, is a section on the line IV—IV of Figs. 1 and 3 looking in the direction of the arrow, also on an enlarged scale.

Referring now to the drawings, in which the various parts are indicated by the same numerals in all the views. 1—1 are the legs of the cot having side rails 2 between which a canvas top 3 is stretched to form a bed. The side rails 2 are notched as shown at 4 in Fig. 4, to receive the end of struts 5, 5^a, two of which are used at each end to support the shelter tent, which is preferably made up of a center section 6 and two end sections 7, 7^a. The center section 6 is provided near each end with double pockets 8, 8^a adapted to receive and snugly hold

the upper ends of the struts 5, 5^a respectively, and also with flat loops 9, 9^a which lie between the pockets 8, 8^a respectively and the tent proper. The pockets 8 and the loop 9 are made of heavy canvas but in order to more clearly show the construction they have been shown in Figs. 3 and 4 as of much greater thickness, so that in these views there is apparently a very considerable thickness of material between the ends of the struts 5 and the canvas of the center sections 6, whereas as a matter of fact the entire thickness including the tent canvas is ordinarily only five thicknesses of heavy cloth. The pockets 8 and the loop 9 are firmly attached by sewing or otherwise as may be desired to the tent canvas. 10 is a cord fastened in one side of the loop 9 which extends the length of the center section 6 instead of a ridge pole and is fastened into a similar oppositely disposed loop 9^a. 11 is a cord passing through the opposite end of the loop 9 the two ends of which cord extend downward and loop around the end of the side rails at the ends 12. A similar cord 11^a passes through the opposite loop 9^a and is adapted to similarly loop around the opposite ends 12^a of the side rails.

The end section 7 is attached to two of the struts 5 by wrapping the edge 15 of the cloth around the strut 5 and securely nailing it thereto with rails 16 and the opposite end section 7^a is likewise attached to the corresponding struts 5^a so that the shelter when down comprises three pieces, namely a center section provided with pockets for the ends of the struts, and with a cord or rope ridge pole and guy ropes attached, and two similar end sections each attached to two struts.

In setting up the shelter tent, after the cot has been opened up, the upper ends of the two struts 5 are placed in the pockets 8, the lower ends in the notches in the side rails, and the ends of the cords 11 are looped around the corresponding ends 12 of the side rails, the other struts 5^a are then placed in the pockets 8^a, their lower ends in the corresponding notches and the cords 11^a in the side rails are pulled tight and hooked over the ends 12^a of the said side rails. Cords 13 are passed through loops 14 and these are then similarly looped over the ends of the side rails. If desired additional cords may be passed through the loops 15 and 110

these may be firmly tied, at the same points.

It will be especially noted that the pockets 8 and 8^a are made up of heavy canvas shaped to fit around the upper end of the struts 5, 5^a and are each securely fastened together at the center point so as to make a double pocket, that over each a strip of canvas is folded to form a double loop 9, 9^a, the two ends of each strip being brought together 10 and lapped and each corresponding pocket, and loop and the adjacent canvas of the tent are firmly fastened together, so that the center section of the shelter tent and the loops 9 and 9^a and the pockets 8 and 8^a make 15 a single unit. It will be further noted that the structure is strengthened by connecting the inner ends of the loops 9 and 9^a by a cord 10 which in addition forms a ridge pole of the tent. It will also be noted that 20 the struts 5 and the end 7 and the struts 5^a and the end 7^a are each integral units, the canvas being firmly fastened to the said struts.

It will thus be seen that when the tent is 25 taken down for transportation, it can be compactly rolled and will occupy a minimum of space and that in erecting it will be in convenient units which lend to ease and convenience in erection.

Having fully described my invention what I claim and desire to secure by Letters Patent in the United States is:—

1. In a shelter tent the combination with 30 cot rails having notches therein, of a center section of fabric, pockets attached to said center section near the ends thereof, a double loop interposed between the said pockets and the said fabric, a ridge cord extending from loop to loop beneath the said 35 fabric, guy ropes passing through the opposite ends of said loops and adapted to be caught around the ends of the said cot rails, struts for each end of the said center section adapted to engage the said pockets and to 40 extend downward to and engage notches in the said side rails, end sections of fabric fastened to the said struts and means for

fastening the edges of the said center section to the ends of the said cot rails.

2. In a shelter tent the combination with 50 cot rails having notches therein of a center section of fabric, pockets attached to said center section near the ends thereof, guy ropes attached to the ends of the said section and adapted to be caught around the ends 55 of the said cot rails, struts for each end of the said center section adapted to engage in the said pockets and extend downward to and engage notches in the said side rails, end sections of fabric fastened to the said struts 60 and means for fastening the edges of the said center section to the ends of the said cot rails.

3. In a shelter tent, a center section of 65 fabric, pockets attached to the said center section near the ends thereof, a double loop interposed between the said pockets and the said fabric and securely fastened thereto, a cord extending from loop to loop beneath said fabric, guy ropes passing through the 70 opposite ends of said loops, struts for each end of said center section adapted to engage said pockets and extend downward and support the said shelter tent, end sections of 75 fabric securely fastened to the said struts and means for fastening the edges of the said center section.

4. In a shelter tent a center section of fabric, pockets attached to the said center section near the ends thereof, guy ropes attached to the opposite ends of the said center section, struts for each end of the said center section adapted to engage in the said pockets and extend downward to support the said center section, end sections of fabric 85 securely fastened to the said struts and means for fastening the edges of the said center section.

In testimony whereof I have hereunto set my name.

WILLARD E. MARSH.
